UNITED STATES PATENT OFFICE.

WINTHROP A. CLARK, OF STAMFORD, CONNECTICUT.

LUBRICATING DEVICE.

1,165,227.

Specification of Letters Patent. Patented Dec. 21, 1915.

Application filed March 6, 1914, Serial No. 822,908. Renewed July 29, 1915. Serial No. 42,646.

To all whom it may concern:

Be it known that I, WINTHROP A. CLARK, a citizen of the United States, residing at Stamford, in the county of Fairfield and State of Connecticut, have invented certain new and useful Improvements in Lubricating Devices, of which the following is a specification.

This invention relates to lubricating devices, among the objects of the invention being the provision of an article of this character which is simple in construction, effective and positive in action.

In the drawings accompanying and forming part of the present specification I have shown in detail one of the several convenient forms of embodiment of the invention which to enable those skilled in the art to practice the same will be set forth fully in the following description. I do not restrict myself to this disclosure; I may depart therefrom in several respects within the scope of the invention defined by the claims following said description.

Referring to said drawings: Figure 1 is a vertical sectional view of a hydrocarbon-engine equipped with a lubricating-device involving my invention. Fig. 2 is a horizontal section on the line 2—2 of Fig. 1. Fig. 3 is a cross section on the line 3—3 of Fig. 2.

Like characters refer to like parts throughout the several views, which it will be observed are on different scales.

A lubricating device embodying my invention can be employed with advantage in many different connections, although it is of especial utility when incorporated in a hydrocarbon or other motor. In this particular field it may be put to several different uses, although it is of prime advantage when used for lubricating the wrist-pin or its bushing, the wrist pin being as is known, the pivot which connects the piston with the connecting rod or equivalent part in a motor of the kind set forth.

In Fig. 1 I have shown the cylinder 2 and the piston 3 of a hydrocarbon engine of the kind using kerosene or coal-oil as the propulsive agent, but as will be obvious the invention is not limited in this respect. The piston 3 is of the so-called "trunk" type. The piston and cylinder both being, therefore, old and not new with me, require no specific description. It is, of course understood that the interior of the piston has communication with the interior of the

crank-case, and the reason for this will hereinafter appear. Inside the piston 3 are diametrically-opposite bosses 4 and 5, which receive the hollow wrist pin 6. Surrounding said wrist pin between the two bosses is the bushing 7 which is clamped in the upper end of the connecting rod 8 connected in the ordinary manner with the crank shaft (not shown). Extending through the top of the wrist-pin 6 are ports 9 and 10 which register with ports 11 and 12 respectively in the upper parts of the two bosses 4 and 5. Interiorly and exteriorly of the wrist pin 6 at that part surrounded by the bushing 7 are longitudinally-extending channels or grooves 13 and 14, the upper groove being connected with the lower groove by ports or perforations 15.

It will be clear that on the up stroke of the piston 3 a partial vacuum is created within the piston, by virtue of which oil or equivalent lubricant can be sucked into the wrist pin or analogous element to lubricate the same, that is to say owing to the partial vacuum within the piston, atmospheric pressure can force oil or equivalent substance into the wrist-pin. The means shown for accomplishing this result will be hereinafter described. It will be assumed that oil is to be drawn into the wrist-pin. In this event the oil enters the channel 14, passes through the ports 15 into the lower channel 13 where it can lubricate the engaging surfaces of the wrist-pin and bushing, the air that is associated with the oil being separated therefrom and passing in the present case through registering ports 9 and 11 and 10 and 12 into the upper portion of the piston. This is merely one of several ways of separating the air from the oil. Radically different means within the scope of the invention might be substituted therefor, the invention as will be inferred not being limited to any particular details in this respect.

The piston 3 is provided exteriorly with a longitudinally-extending channel 16 of such length as to be in communication at all times with the port or opening 17 in the cylinder 3. Leading from the channel 16 inwardly is a passage or port 18 from which the pipe 19 extends, said pipe having a downturned portion 20 located over the channel 14, to which I have already referred. Threaded or otherwise fitted into the outer portion of the port 18 or passage 17 is the boss 22 of the valve casting 23 which has a practically Z-shaped

longitudinal passage 24 controlled by the outwardly-opening check-valve 25 normally held to its seat by the spring 26 acting thereagainst and also against the screw-plug 27 tapped into said valve casing 23. The outer end of the passage 24 is closed by the plug 28 which may as shown consist of a screw. Opening into said passage in proximity to said screw 28, is a supply-pipe 29 for the lubricant which may be under forced-feed or may be conducted toward the passage 24 by gravity. Fitted, by threading or otherwise into the valve casing 23 is a tube 30, the interior of which is connected by the port 31 with the passage 24, the tube 30 having a cap 32 and also as illustrated, having diametrically opposite openings 33 to atmosphere.

It will be assumed that the piston 3 is moving upward, for example to compress the charge of gas in advance of it. This upward movement of the piston constitutes in the showing made, the oil-suction stroke of the piston. On such movement of the piston there will be created therein a vacuum so that the atmospheric air passing into the tube 30 by way of the two ports 33 can enter the channel 24 by way of the port 31, carry or force the oil with it, lift the valve 25 from its seat, pass through the boss 22, port 17, channel 16, port 18 and pipe or tube 19 leaving the delivery end 20 of the latter into the channel 14. The air mixed with the oil leaves the oil as soon as the two are discharged from the pipe 20 and ascending the wrist pin is discharged through the two pairs of registering ports 9 and 11 and 10 and 12 respectively into the upper part of the piston, so that the oil wholly free of air will pass through the two ports 15 into the channel 13 where it can lubricate the engaging portions of the wrist-pin 6 and bushing 7.

It will be noted that I provide a positive, certain way of oiling a wrist-pin and its bushing and that the oil and air together are thrown into the wrist-pin where the air or some similar fluid is separated from the oil. It will be also perceived that the parts can be readily cleaned. I desire also further to note the important fact that the interior of the wrist-pin or equivalent is adapted for communication with the atmosphere, the valve 25 or one of a similar nature being provided to prevent the oil that is sucked into the wrist pin, being blown back into the valve casing or other container 23. There may be cases where I might dispense with the valve.

It will be clear from the foregoing description taken in connection with the annexed drawings that I provide in combination with a cylinder and a piston, duct means connecting the interior of the cylinder with the atmosphere, means for supplying a lubricant to the duct means, the piston being adapted to draw the lubricant into the

cylinder by way of said duct means, and means whereby the oil and the air can be separated from each other within the cylinder. Of course, other parts might be substituted for the cylinder and the piston provided the equivalent of the piston possessed the function of drawing in the oil in the manner noted, and there may as practically remarked, be cases where an agent other than the atmospheric air could be utilized for aiding the feed of the lubricant.

As a part of the invention I also claim the method of lubricating an engine which comprises the step of drawing the lubricant into the interior of the cylinder by the suction of the piston and then in separating the air from the lubricant inside the cylinder or equivalents.

It will be noted that there is an uninterrupted or unobstructed passage connecting the valve casing 23 with the interior of the piston 3 so as to facilitate cleaning, in that when said valve casing is dismounted the wrist pin can be cleaned without removing any of the other parts of the engine.

What I claim is:

1. The combination of a cylinder and a piston within the cylinder, one of the parts having a channel extending longitudinally of the cylinder, and both having ports in constant communication with said channel, means for supplying lubricant into said channel through the port in the cylinder, a hollow wrist pin mounted in the piston, and means for conveying lubricant from the port in the piston, into said wrist pin, the latter having an outlet for the lubricant.

2. The combination of a cylinder having a port, a piston reciprocatory in the cylinder, having a longitudinally extending channel in constant communication with said port, means for supplying lubricant by way of said port to said channel, and a hollow wrist pin in the cylinder, and means for conveying lubricant from said channel into the wrist pin, the latter having an outlet for said lubricant.

3. The combination of a cylinder, a piston in the cylinder, a hollow wrist pin connected with the piston, means for conducting lubricant into the wrist pin, the latter having an outlet for the lubricant, said wrist pin and piston having registering ports for the passage of air from the interior of the wrist pin into the interior of the piston, the interior of the piston being in communication with the interior of the cylinder.

4. The combination of a cylinder, a piston in the cylinder, a hollow wrist pin connected with the piston, a bushing surrounding the wrist pin, the wrist pin having communicating channels in its inner and outer surfaces, the outer channel being between the ends of said bushing, and means for delivering lubricant into the inner channel.

5. The combination of a cylinder, a piston in the cylinder, the piston on its exterior having a longitudinally extending channel, a source of lubricant supply, passage means connecting said channel with the atmosphere and with the source of lubricant supply, a hollow wrist pin connected with the piston, a bushing surrounding the wrist pin, a port extending from the interior of the wrist pin 10 to the space between the wrist pin and the bushing, means for conducting oil and air received from said channel into the lower portion of the wrist pin, the wrist pin having communication with the interior of the 15 piston to provide for the escape of air from the wrist pin into the piston.

6. The combination of a cylinder, a piston provided with a wrist pin, means for uninterruptedly conveying lubricant from a 20 point outside the cylinder to the wrist pin while the piston is in motion and in the various positions of said piston, the latter be-

ing adapted to positively draw the lubricant along said conveying means by and during said motion, and means whereby the lubricant and air are separated from each other 25 at the wrist pin.

7. The combination of a cylinder and a piston, means for uninterruptedly conveying lubricant from a point outside the cylinder 30 into the same to lubricate a desired area, and in different positions of the piston, the latter being adapted to positively draw the lubricant along said conveying means by and on the motion thereof, and means whereby 35 the air and lubricant are separated from each other approximately at the area which is being lubricated.

In testimony whereof I affix my signature in presence of two witnesses.

WINTHROP A. CLARK.
